DESIGN FOR A HANDLE FOR KNIVES, FORKS, SPOONS, AND SIMILAR ARTICLES

Nathaniel Mirsky, Brooklyn, N. Y., assignor to H.
Boker & Co. Inc., New York, N. Y., a corporation of New York

Application July 6, 1938, Serial No. 78,310

Term of patent 7 years

To all whom it may concern:

Be it known that I, Nathaniel Mirsky, a citizen of the United States, residing at Brooklyn, in the county of Kings, and city and State of New York, have invented a new, original, and ornamental Design for a Handle for Knives, Forks, Spoons, and Similar Articles, of which the following is a specification, reference being had to the accompanying drawing, forming part thereof.

Figure 1 is an elevation of a handle as viewed from either one of two opposite sides showing my new design;

Figures 4, 5 and 6 are sectional views taken on lines 4—4, 5—5 and 6—6 respectively of Figure 1.

I claim:

The ornamental design for a handle for knives, forks, spoons, and similar articles, substantially as shown.

NATHANIEL MIRSKY.
